CLAIM

I claim the ornamental design for a food saver, as shown and described.

DESCRIPTION

FIG. 1 is a top perspective view of a food saver in a closed configuration, showing my new design.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a top perspective view of the food saver in an open configuration.

The broken lines show portions of the food saver and form no part of the claimed design. The areas between the broken lines and solid lines edges form no part of the claimed design.
